LEAD WIRE FEED MECHANISM FOR LAMP
STEM FABRICATING APPARATUS

Stanley J. Gartner, Emporium, Pa., and Samuel E. Swasey, Marblehead, and Dwight J. Dwinell, Reading, Mass., assignors to Sylvania Electric Products Inc., Salem, Mass., a corporation of Massachusetts

Application October 19, 1946, Serial No. 704,316

2 Claims. (Cl. 140—132)

1

This invention relates to automatic machines for fabricating glass stem elements for lamps or thermionic devices.

The present invention is specifically directed to means for dispensing lead wires to the stem assembly and relates to subject matter presented in an application for a United States patent in the names of Roland M. Gardner, Stanley J. Gartner and Edwin W. Barrett for Automatic Lamp Stem Fabricating Apparatus and bearing Serial Number 637,440, now Patent No. 2,637,144 issued May 5, 1953.

Figure 1 is a front elevation of the lead wire dispensing mechanism;

Figure 2 is an enlarged side view of the lead wire pick up finger;

Figure 3 is a front view of the lead wire pick up finger;

Figure 4 is a detail view of the lead wire pick up finger and its actuating mechanism;

Figure 5 is a detail side elevation of a modified form of pick up finger mechanism;

Figure 6 is a partial cross sectional view of the mechanism shown in Figure 29;

Figure 7 is a side elevation of a cam for operating the pick up fingers; and

Figures 8, 9 and 10 are detail views of pick up fingers showing different forms of pick up finger slots.

Figure 11 is a perspective view of the lead wire reservoir.

The lead wire dispensing apparatus is disposed on the stem machine in register with the path traversed by the stem machine heads which are carried to a plurality of work stations.

When the stem machine head arrives at the lead wire feeding station a pair of wires precut to proper length is fed to the flare. The means for feeding the wires contains duplicate mechanisms each of which manipulates a single wire simultaneously. The wires 44 are stacked in parallel relation in hoppers 136 secured upon a horizontal supporting plate 137. The plate is mounted upon a rigid post 138 which is adjustably secured in a rigid column 139 secured to a bracket 140 which in turn is secured to and extends laterally outward from the platen 6 of the stem machine. Desirably the platen is provided with one or more grooves 141 within which a key upon the bracket is received.

A single wire is picked from the stacks by a pair of identical fingers 142. The innermost wires of the stacks are supported at their end portions only to permit the fingers to engage their middle portions. The fingers are vertically reciprocated

2

by means of a yoke 143 secured to an actuator rod 144 which travels vertically within the post 138 and extends downward and is guided through the column 139 and bracket 140. The rod 144 is driven by a cam 145 on the cam shaft 33. The cam in turn actuates a lever 146 fulcrumed upon the shaft 40, and has on its outer end a roll to engage the bottom face of the rod. The rod is held against the cam lever by a compression spring surrounding the rod and bearing at one end on the bracket 140 and at its other end against a collar on the rod.

The fingers 142 are freely pivoted upon the lower end of vertical rods 148 which are slidable in the yoke 143 and have stop shoulders at the upper end to cause them to be drawn upward by the yoke. The object of the free movement of the rods in the yoke will appear hereinafter.

The fingers 142 are provided with inwardly projecting arms 149. The rods 148 also have short rigid arms 150 above the arms 149. A compression spring 151 is received between the arms 149 and 150 and acts to swing the arms outward into engagement with the vertical edge of the pile of wires in the hoppers. The vertical motion of the fingers derived from the cam moves them over the inner edge of the stack of wires and in so doing a single wire is picked from the pile by each finger and enters horizontal grooves 152, in the fingers under the action of suction induced by small hole 153 leading to ducts 154 extending up through the fingers. The duct 154 connects with the opening in hollow pivot pins 155 upon which the fingers swing. The pivot pins are extended to receive a flexible tubing connected to a suction pump or other vacuum device not shown.

A feature of the invention resides in the construction of the fingers 142 which are provided with one or more small slots 156 extending transversely of the grooves 152. The slots 156 prevent the fingers from picking up more than one wire at a time since they act to greatly reduce the suction upon any wire but that which is accurately positioned in the groove 152.

The fingers 142 are provided with short projections 157 extending outward adjacent their pivots. At the end of the upward travel of the fingers the projections 157 engage pins 158 which are rigidly fixed in a cross bar 159 mounted on a support extending upward from the plate 131. Engagement with the pins causes the fingers to swing inward and in so doing pass between a pair of stripper wires 160 fixed in supports secured to plate 137. The wires 160 strip the wires 44 from the fingers from where they fall into a pair of

chutes 161 having a funnel shaped upper portion into which the lead wires fall in a substantially horizontal position and are tipped up into a substantially vertical position thereby to then travel through the lower cylindrical portions of the chutes.

From the chutes 161 the wires pass into a pair of feeding or shuttle devices 162 which feed the wires into the flare. The shuttle members are spaced apart the distance between successive heads on the conveyor and each shuttle feeds one wire to each flare so that in two successive indexing operations the flares receive their two lead wires.

It is desirable that the fingers 142 be reciprocated in contact with the wires a plurality of times. Means for doing this is shown in Figure 7 wherein the cam 145 for operating the finger actuating rod 144, is provided with a contour properly shaped to produce the desired motion. The cam is shaped to produce an overall traverse of the finger sufficient to effect the various functions thereof above described and is further provided with a depression 186. Other similar depressions or raised lobes on the cam may be provided. The depression is situated on the cam to cause a small up and down motion of the finger while it is in contact with the lead wires. This extra up and down motion of the fingers tends to maintain all lead wires near the fingers in true mutual parallel alignment thus insuring consistent pick up of the wires by the finger.

As above described the wires are picked out of the stack by suction and stripped from the finger by mechanical means. Other than mechanical means may however be used to strip the wire from the finger.

A very efficient device for holding and releasing the lead wires is shown in Figures 5 and 6. In this device the finger is mechanically actuated in the same manner as above described and suction applied to the suction duct, acts to withdraw a single wire from the stack of wires and hold it until it is released to fall into the channel means carrying it to the flare below. In the form of the invention presently being described however, a positive air pressure is applied at the finger groove to release the wire. This may be accomplished in any suitable manner. As herein shown the fingers 142 are provided with hollow pivot members 187 having an extension thereon to form a valve mechanism 183. Desirably the extension of the pivot 187 has a chamber 189 therein communicating with the opening in the pivot and also a cylindrical spindle portion 190 in axial alignment with the pivot. The extension 187 also is provided with a flat face 191 in a plane at right angles to the pivot axis. A valve plate 192 is centrally apertured and rotatably mounted on the spindle. The plate 192 is provided with a flat face which is held firmly against the face 191 by a spring 193 on the spindle. The outer end of the spring 193 is backed by a collar 194 fixed to the spindle. The plate 192 is provided with a pair of ports 194 and 195 which are provided with nipples for connection to a source of vacuum and positive pressure means respectively.

Another pair of ports 196 and 197 are formed in the face 191 of the member 187. These ports are arranged to register with the ports 194 and 195 by movement of the finger. The plate 192 is held against rotation in any suitable manner such as by a stud 198 anchored at its upper end upon the projection 150 and extending into the plate at its other end. Thus movement of the

finger 142 produces relative movement between the plate 192 and the member 187.

The position of the various ports in the valve are such that when the finger is in its substantially vertical position wherein a wire is picked up one port in the plate 192 and one in the member 187 are in register for example the ports 194 and 197 in which case the nipple connected to the port 194 would be connected to the source of vacuum.

When the fingers are in their raised position and swung into position to release the wire the two ports 195 and 196 are in register while the ports 194 and 197 are out of register. The nipple connected to the port 195 is connected to a source of low air pressure thus the wire is projected from the slot in the finger and falls into the wire conducting chute 161 from where it goes to the flare as above described.

The pick up groove 152 in the finger 142 may have various cross sectional conformations. One efficient form for the slot is that shown in Figure 8 wherein the slot is generally V-shaped in cross section and in which its bottom wall 199 is disposed at an angle slightly less than 90° to the wire removing motion of the finger and extends slightly upward from the front of the finger toward the slot apex.

The wall 199 disposed at the angle shown acts to positively hold the wire after it has been sucked into the slot and while it is being drawn upward along the mass of wires where the tendency toward dislodgement is greatest. Moreover, this conformation of the slot also insures free disengagement of the wire when it is stripped from the finger.

Other cross sectional forms for the slot may be employed such as the rectangular slot 200 shown in Figure 9 and Figure 10. In this form of finger not only is the wire pick up slot 200 rectangular but the cross slots 201 are also rectangular and of substantial width. It has been found that this combination of slots functions very efficiently particularly when the slot 200 is made only slightly wider than the diameter of the wire.

What we claim is:

1. Wire dispensing apparatus comprising: a reservoir for the wires, said reservoir having an opening in a wall thereof exposing the wires lying thereagainst; an elongated finger, for picking wires individually from said reservoir, mounted above said reservoir with a portion thereof lying opposite the opening in the wall of said reservoir, said finger having a duct therein extending longitudinally thereof and terminating at one end in a hole in a wire-receiving horizontal groove formed in one end of said finger, said finger having at least one slot cut in said end thereof transversely of said horizontal groove; means for connecting the other end of said duct to a vacuum source; and means for actuating said finger, to move it into engagement with the wires exposed by the opening in the wall of said reservoir.

2. Apparatus for dispensing wires comprising: a reservoir for the wires, said reservoir having an opening in a wall thereof exposing the wires lying thereagainst; an elongated finger, for picking wires individually from said reservoir, pivotally mounted above said reservoir and extending downwardly with a portion thereof disposed opposite the opening in the wall of said reservoir, said finger having a duct therein extending substantially longitudinally thereof and terminating at one end in a hole in a wire-receiving horizontal groove formed in the wall of said finger facing

the opening in the wall of said reservoir, said finger having at least one slot cut therein transversely of said horizontal groove; means for connecting the other end of said duct to a vacuum source; means for vertically reciprocating said finger; and means for reciprocally rotating said finger about its pivot.

STANLEY J. GARTNER.
